UNITED STATES PATENT OFFICE

2,558,213

CUTTING CHAIN PIN AND LOCK

Charles J. Forbes, Terre Haute, Ind.

Application February 20, 1947, Serial No. 729,788

1 Claim. (Cl. 74—254)

1

This invention relates to machinery suitable for the cutting of coal and the like.

The invention is primarily directed to the pivotal connection between links of a cutting chain having cutters or bits supported by certain of the links.

The chief object of the present invention is to lock the pin means to one of a pair of adjacent links or link means so that relative rotation of the pin means and said one link or link means is prevented and the adjacent links are pivotally secured together and the pin means is locked against axial separation.

The chief feature of the present invention resides in forming one end of a tubular barrel or pin with a flat face or flat faces to mate with a corresponding face or faces upon the link to which the pin is to be secured and secure such tubular barrel to that link by a headed stem having the headless end deformable to rigidly secure the barrel and stem together, the barrel and/or stem having a laterally enlarged portion or portions nestable in a link recess or recesses, respectively.

Other objects and features of the invention will be set forth more fully hereinafter.

The full nature of the invention will be understood from the accompanying drawings and the following description and claim.

In the drawings—

Fig. 1 is a side elevation of a pair of pivotally connected links one being of straddle type, and the pivotal connection therebetween.

Fig. 2 is a central sectional view through the same.

Fig. 3 is a perspective view of the barrel and headed stem in disassembled position.

Fig. 4 is a view similar to Fig. 1 of a second embodiment of the invention, the view being taken from the same side but of the other end of a corresponding link.

Fig. 5 is a central sectional view, similar to Fig. 2 and of the form of the invention shown in Fig. 4.

Fig. 6 is a perspective view of the barrel and headed stem shown in Figs. 4 and 5 and in disassembled position.

In Figs. 1 to 3 of the drawings there is illustrated one embodiment of the invention while Figs. 4 to 6 illustrate another. In Figs. 1 and 2, 10 indicates a connecting link having at opposite ends the bores for barrel reception. 11 indicates such a bore.

In Fig. 1, 12 indicates the connecting portion connected to spaced portions 13 and 14, see Fig. 2, of a straddle type link which includes a support, not shown, in turn supporting a bit or a

2

detachable holder and bit, as well known in the cutter chain art.

At opposite ends said straddle link is provided with aligned bores in portions 13 and 14. In Fig. 2 plate 13 includes a cylindrical bore 15 counterbored externally as at 15a. Portion 14 has aligned bore 16 shouldered as at 16a. Herein shoulders 16a are parallel. Bore 16 is externally counterbored at 17.

10 The cylindrical barrel 18 includes central bore 19 therethrough, counterbored at one end as at 20 and at the opposite end at 21. The former end is conically flanged at 22 which is seatable in counterbore 15a of the link portion 13. The barrel opposite the flanged end is shouldered as at 23 and providing parallel flat faces 24.

The headed stem comprises cylindrical portion 25 with conical enlargement 26 and head 27 conically edged as at 28.

20 The method of assembly is as follows: The two links are lapped as shown in Fig. 2 and barrel 18 presented shouldered end first to bore 15 and rotated if necessary to register faces 24 with faces 15a. When fully seated flange 22 seats in counterbore or recess 15a thus limiting inward or longitudinal movement of the barrel.

If flange 22 were omitted shoulders 23 could be disposed more forwardly and then engage the inside face of portion 14 and effect functionally the same result.

When properly seated the stem is presented free end first to the faced end of the barrel. When fully seated, portion 26 seats in barrel counterbore 21 and flange edge 28 seats in counterbore 17 of link portion 14. The stem then projects beyond the barrel as shown by dotted lines 30 in Fig. 2. When so seated that end is enlarged as shown at 29 in said figure thus filling counterbore 29 and locking the parts together.

Hence axial displacement of the barrel in the several link aligned bores is prevented and rotation relative to the straddle link is also prevented and the links in effect are riveted together in pivotally connected relation.

Reference will now be had to Figs. 4 to 6 inclusive where a modified form of the invention is illustrated. Herein the stem is T-shaped and the tubular pin barrel omits the flange at the end opposite the shoulders and faces.

In this embodiment, see Fig. 6, 125 indicates 50 the stem and 127 the head or cross-piece. The cylindrical tubular barrel 118 includes central bore 119 and shoulders 123 and adjacent faces 124 at one end. At this end also, and transverse to faces 124 is end groove 131.

Link portion 114 has bore 116 with flat, sub-

stantially parallel faces 116^a and a transversely disposed groove 117. Same registers with barrel groove 131 when barrel shoulders 123 engage against the inside face of link portion 114.

Link 110 includes cylindrical barrel receiving bore 111. The opposite link portion 113 has cylindrical bore 115. The barrel 118 opposite the grooved end includes counterbore 120.

Barrel 118 is registered slotted end first through bore 115 and bore 111 until the shoulder engagement described is effected. Then the stem is applied to the barrel bore and passed reversely therein until head 127 seats in barrel groove 131 and the projecting ends seat in link recess or groove 117. This prevents stem passage through the links.

The projecting end 130, see dotted lines in Fig. 5, is then deformed as at 129 to seat in barrel counterbore 120. In this manner, as before, the barrel and stem are oppositely presented to the lapped links and the final locking as by enlargements 29 and 129 is effected at the side from whence initial barrel presentation is effected.

Whenever release is required, enlargement 29 or 129 is removed from the stem and later driven out of the barrel toward the head of the stem. Also the barrel may then be reversely withdrawn from the links, the link substitution effected, the barrel replaced and a replacement headed stem applied as before.

While the invention has been illustrated and described in great detail in the drawings and foregoing description, the same is to be considered as illustrative and not restrictive in character.

The several modifications described herein as well as others which will readily suggest themselves to persons skilled in this art, all are considered to be within the broad scope of the invention, reference being had to the appended claim.

The invention claimed is:

A cutter chain structure comprising, in combination, a center link and a pair of overlapping side links, said links having registering bores therein, each of said side links having a conical bore in its outer face, a connecting barrel seated in the registering bores having at one end a conical head seated in a conical bore in the outer face of one of said side links with its top lying flush with the outer face of the link, the bore of the opposed side link having a flattened side adapted to cooperate with a flattened shoulder of the link barrel, said barrel being such that its opposite end is flush with the bottom of the counterbore of the second side link, one end of said barrel having a counterbore below the outer face thereof, and a headed locking pin extending through said links and barrel having an enlarged head seated in the counterbore in the second mentioned side link and lying flush with the outer face of the link, and having its opposite end headed into a counterbore of said barrel and lying flush with the outer end of said barrel.
